(57) **CLAIM**

The ornamental design for a garment pocket, as shown and described.

DESCRIPTION

FIG. 1 is a top, right, and front isometric view of a garment pocket showing our new design;

FIG. 2 is a bottom, left, and front isometric view thereof;

FIG. 3 is a bottom, left, and back isometric view thereof;

FIG. 4 is a top, right and back isometric view thereof;

FIG. 5 is a top plan view thereof;

FIG. 6 is a front elevation view thereof;

FIG. 7 is a right side elevation view thereof;

FIG. 8 is a back elevation view thereof;

FIG. 9 is a left side elevation view thereof;

FIG. 10 is a bottom plan view thereof; and,

FIG. 11 is a right, front isometric view thereof, showing the garment pocket of FIG. 1 in an alternate environment of use. The broken lines in the drawings illustrate environmental structure that forms no part of the claimed design.

1 Claim, 5 Drawing Sheets
